INVENTOR

Frank M. Ashley

UNITED STATES PATENT OFFICE.

FRANK M. ASHLEY, OF BROOKLYN, NEW YORK.

FOUNTAIN PEN.

Application filed December 1, 1928. Serial No. 322,996.

My invention relates to fountain pens. The object of my invention is to provide a self filling fountain pen of the piston type, which is easy to fill and in which the parts 5 are made so as to eliminate friction between the piston and wall of the pen, and between the piston rod and packing therefor, to a minimum degree. A further object is to provide a pen that has a large ink capacity 10 and which may be filled by inserting the front end of the feed plug only, into the ink container.

The specific invention and the advantages of this construction will be pointed out hereinafter.

Referring to the drawings which form a part of this specification:

Fig. 1: is a longitudinal sectional view of a fountain pen embodying my invention. 20 Fig. 2: is a cross sectional view, taken on line 2-2 of Fig. 1.

A— indicates a cylindrical barrel having a smooth cylindrical bore or wall A'— formed therein, and enlarged at A²— to 25 provide a by-pass for ink. A pen section B— is connected to the barrel by a thread C— and a feed plug D— is fitted into the pen section in the usual manner. The feed plug D— is provided with the usual feed duct 30 D²— and with a central bore D'— which extends entirely therethru. E— indicates a small tube of glass or hard rubber, which is held firmly in the bore D'— and extends about half way to the middle of the barrel 35 A. F— indicates a piston which is fitted to slide freely in contact with the surface of the bore A'— and which is of less length than the length of the by-pass chamber A²— in which it normally rests. The piston is 40 provided with a tubular piston rod portion F'— preferably formed integral therewith, the bore F²— of which fits over the surface of the tube E— in close sliding engagement. The piston rod portion F'— is provided 45 with a hole G— located near its end, as illustrated, and the end of said tube is fitted over and fastened to the inner end of a hard rubber tube I. The tube I— is reinforced by a stiff steel rod J— which completely 50 fills said tube throughout its length. A soft rubber plug K— is fitted in tight abutment against the end of the tube I— and rod J— and serves to close the end of the tube E— and also to prevent ink from coming in contact with the metal rod J. The 55 tube I— and tube F'— serve as a piston

rod, which extends through the end plug and is provided with a handle N. The plug is provided with packing material M— and gland nut M'. The handle N— is provided 60 with a threaded projection N'— on its inner side, which screws into the threaded end of the plug L, and when screwed therein as shown, causes the end of the inner tube E— to abut the plug K—, or if it does not abut, causes the end of the inner tube E— to extend beyond the hole G— and closes the same, at which time the piston F— will rest in the by-pass chamber A²— as shown, and open communication 65 between the reservoir O— and the feed duct D²—, the passage through the bore D'— and hole G— being closed to prevent air from entering the reservoir through said bore. The end F³— of the 70 tube F'— serves as an abutment to limit the outward movement of the piston rod during the filling operation. It is obvious that the tubular portion F'— could be made long enough to extend through the end plug 75 L— and thus dispense with the smaller tube I—, but this would require a larger stuffing box and increase the friction of the contacting surfaces, and also make it more difficult to keep a tight joint; also it would reduce 80 the ink capacity of the reservoir O—.

This construction provides a short stroke pen which permits the use of a rod of small diameter, whereas a long rod is apt to bend in the filling operation, and cause the packing to leak. The operation of filling is as 85 follows:

Insert the end of the feed plug D— below the surface of the ink in the container, and reciprocate the piston two or three 90 times: on the outward strokes of the piston rod, the air in the reservoir is forced out through the hole G— tube E— and bore D'— and on the inward strokes the ink is 95 drawn in thru said elements to fill the reservoir.

Having thus described my invention, I claim as new:

1. A fountain pen comprising a barrel having a smooth cylindrical reservoir closed at one end, a pen section held at its opposite end, a feed plug in said section having an ink duct and a bore extending longitudinally thereof, a tube extending from said bore into said reservoir, a piston having a tubular rod 105 extending over said tube and having an opening located a predetermined distance from 110

said piston and serving as a passage between said reservoir and said first tube, and means for closing said passage; the construction being such that two or more successive outward strokes of the piston rod will expel air from the reservoir and the inward strokes will draw ink therein.

2. A fountain pen constructed as set forth in claim 1, together with means for limiting the outward stroke of the piston rod.

3. A fountain pen comprising a barrel having a smooth cylindrical reservoir closed at one end by a piston rod, a pen section held at its opposite end, a feed plug in said section having an ink duct and a bore extending longitudinally thereof, a tube extending from said bore into said reservoir, a piston hav-

ing a tubular rod extending over said tube and having an opening located a predetermined distance from said piston and serving as a passage between said reservoir and said first tube, said tubular rod having an extension rod of smaller diameter connected thereto which extends thru said closed end of the barrel.

4. A fountain pen having the construction defined in claim 3, together with means for reinforcing said extension rod, and means for shielding said reinforcing means from contact with ink.

In testimony whereof I have affixed my signature.

FRANK M. ASHLEY.
